UNITED STATES PATENT OFFICE.

ROY W. SCHWEIKER, OF LANSDALE, PENNSYLVANIA, ASSIGNOR TO FRANKLIN POT-
TERY, OF LANSDALE, PENNSYLVANIA, A CORPORATION OF DELAWARE.

ATTACHING BRACKET FOR LIGHTING FIXTURES.

Application filed March 11, 1925. Serial No. 14,662.

This invention relates to attaching brackets for lighting fixtures and is particularly intended for use in connection with ceiling fixtures.

5 The object of the invention is to provide a novel combined lamp socket mounting and fixture attaching bracket by which the lamp socket will be securely held in position and the fixture will be attached to the electric outlet box.

10 My purpose is to provide an attaching bracket which may be quickly and easily attached to the outlet box in readiness for the rapid assembly therewith of the fixture and the lamp socket, with accessibility for detachment of the fixture and the lamp socket at any time, on removal of the shade or globe of the fixture and without necessitating detachment of the bracket from the 15 electrical outlet.

20 The base plate by which the bracket is attached to the outlet may be of any preferred, or approved, construction, whether plain, or adjustable. The fixture may be 25 of any desired, or preferred, construction and appearance.

25 However, the invention is well adapted for use in connection with a special porcelain fixture of novel design such as set forth 30 in my application design for ceiling lighting fixture executed of even date herewith although I wish it understood that I do not limit the present invention to use in connection therewith, nor is the invention 35 restricted to use in connection with a ceiling fixture as it could be adapted to a side wall lighting fixture.

The invention, which is susceptible of 40 modification, is hereinafter fully described and claimed, and is shown in the accompanying drawings, in which:

Figure 1 is a vertical section.

Fig. 2 is a top plan view; and

Fig. 3 is a bottom plan view.

45 The plate 1 by which the device is connected to the usual metal outlet box, not shown, may be of a single piece of metal or two pieces adjustably connected together as will be understood by those skilled in 50 the art.

Screwed into the plate 1 are two rods 2 which are provided with nuts 3 so that they may be adjusted, and clamped in posi-

tion as desired. These rods have screw threaded ends and carry other nuts 4 to hold the lamp socket in position. 55

A metal ring 5, preferably of sheet material serves as a holder for the two-part lamp socket. The lamp socket comprises a porcelain base 6 to which the usual screw threaded metal shell 7 and center contact 8 are fastened in any desired manner, and a porcelain ring 9 which has internal screw threads 10 encircling and engaging the screw threaded shell 7. 60

The porcelain ring 9 is provided with reduced hub 11 which enters an annular cavity 12 in the base 6, said hub being of just the proper size to pass through the central opening in the metal ring 5. 65

A gasket 13, which may be of soft rubber but which could be of other insulating material, is interposed between the porcelain base 6 and the metal ring 5 and surrounds the hub 11. The purpose of the gasket 13 which, preferably, is somewhat compressible, is to enable the porcelain ring 9 to be screwed up against the metal ring 5 to tightly hold the parts together without danger of injuring either the shell 7, ring 9, or tearing the shell 7 from the base 6 and, also, to prevent any rattling in the fixture or the bracket. 70

The rods 2 pass through adjustable spacing bushings 14 which have screw threaded, tapered, ends 15 adjustably screwed into the metal ring 5. These bushings arrange the outer nuts 4 sufficiently below the ring 9 to enable them to be conveniently manipulated and they also provide for desired adjustment. If the ring 5 is of sufficient thickness, the holes therein which receive the screw ends 15 may be threaded but if the ring 5 is so thin that a proper screw thread cannot be tapped in said holes, the tapered screw ends 15 form a thread on the margins 95 of the holes, or, the thickness of the ring 5 may be approximately that of the space between adjacent threads so that a nut-like engagement of the bushings with the ring will result. 100

As previously set forth, the invention may be used in connection with any preferred design of lighting fixture. It is well adapted for use in connection with the lighting fixture disclosed in my aforesaid design application and I have, therefore, illustrated 105

it in connection therewith but do not limit myself to the use of a lighting fixture of that design.

The fixture which is shown at 16 is preferably of porcelain and the rods 2 pass therethrough, the base plate 1 bridging the back of the fixture 16 and the ring 5 resting against the flange 17 of the fixture, thereby supporting the fixture 16 from the metal ring 5. Preferably, the opening through which the rods pass is provided with irregular parts or notches 18 in its margin which engage the rods and thus prevent relative turning of the fixture and the bracket.

15 Any suitable globe or shade may be attached to the fixture 16 by securing it to the fastening devices 19 on the fixture.

I claim:

1. The combination with a one-piece lighting fixture or shell having shade holding means at its lower part, of an attaching bracket for holding the fixture or shell and for mounting a lamp socket, comprising an attaching base plate, an internal supporting member engaged with the lighting fixture or shell above the shade holding means, a lamp socket composed of a base and a ring, said base carrying the electrical terminals and being located on one side of said member, 30 said ring having a detachable connection to said base and engaging the other side of said member, said base and ring clamping the member between them, and detachable connections between the supporting member 35 and the base plate, whereby the fixture, socket, and shade are all suspended from said base plate.

2. In an attaching bracket for lighting fixtures, the combination with a base plate, 40 of a one-piece supporting member engaged with the interior of the fixture above the lower end thereof, said fixture having shade holding means disposed below the point of engagement of the supporting member with 45 said fixture, means depending from the base plate which suspends the supporting member, and a lamp socket comprising a base section which carries a lamp receiving metal shell, and a screw threaded ring section which 50 is fastened to the base section through the medium of its screw threads, the supporting member being located between, and clamped by, the sections of said lamp socket, and a 55 cushioning gasket interposed between one of said sections and said member.

3. In an attaching bracket for lighting fixtures, the combination with a base plate, 60 of a supporting member, a lamp socket carried by said supporting member, rods connected to said base plate, adjustable screw threaded bushings entered in, and carried by the supporting member, said rods passing through said screw threaded bushings, and 65 nuts on said rods outside the screw bushings and a one piece fixture or shell which en-

closes the aforesaid elements and is suspended by said supporting member, said shell having its lower part extending below the socket and provided with means for holding a shade or globe.

4. The combination with a one-piece lighting fixture or shell whose lower part is shaped to receive a globe or shade, and means on the fixture or shell to secure a globe or shade, said fixture or shell having an internal flange located above the globe or shade receiving and holding part, of an attaching bracket for said fixture or shell comprising a supporting member engaged with said flange, a lamp socket carried by said supporting member, and means for attaching the supporting member to an electrical outlet.

5. The combination with a one-piece lighting fixture or shell whose lower part is shaped to receive a globe or shade and is provided with means for the attachment of a shade or globe, said fixture having an internal flange located above its globe or shade receiving part, of an attaching bracket for 55 said fixture comprising a supporting ring engaged with said flange, a lamp socket comprising separable parts clamped on opposite sides of said ring, and means for suspending said ring, whereby the fixture or shell may be suspended.

6. The combination with a one-piece fixture or shell whose lower part is shaped to receive a globe or shade and is provided with means for the attachment of a shade or globe, said fixture having upper and lower internal flanges located above the globe or shade receiving part, of an attaching bracket therefor comprising a supporting member engaged with the under face of the lower flange, a lamp socket carried by said supporting member, a base plate whose ends are engaged with the upper flange on the fixture or shell, and means connecting the base plate and supporting member, whereby the fixture, socket, and shade are all suspended from said base plate.

7. The combination with a one-piece lighting fixture or shell whose lower part is shaped to receive a globe or shade and is provided with means for the attachment of a shade or globe, said fixture having an internal flange located above its globe or shade receiving part, of an attaching bracket for said fixture comprising a supporting member engaged with said flange, a lamp socket carried by said supporting member, a base plate located within the fixture above said supporting member, and a detachable and adjustable suspending device by which the supporting member is hung from the base plate, whereby the fixture, socket, and shade are all suspended from said base plate.

In testimony whereof I affix my signature.
ROY W. SCHWEIKER.
